UNITED STATES PATENT OFFICE.

HARRY HARLAN BOYER, OF WALNUT CREEK, CALIFORNIA.

SUSPENDER ATTACHMENT.

1,094,520.

Specification of Letters Patent.

Patented Apr. 28, 1914.

Application filed February 13, 1913. Serial No. 748,195.

To all whom it may concern:

Be it known that I, HARRY HARLAN BOYER, a citizen of the United States, residing at Walnut Creek, in the county of Contra Costa and State of California, have invented new and useful Improvements in Suspender Attachments, of which the following is a specification.

My present invention relates to suspender attachments, and more particularly to a contrivance of this character designed to facilitate the attachment of the suspender elements to the buttons on the trousers or overalls.

The device employed includes a novel arrangement of resilient elements involving a high degree of elasticity, consequently assuring a firm grip on the button.

Primarily the device is designed to assure a secure connection between the suspender elements and their support, thus assuring the efficiency of the contrivance. However, a careful scrutiny will disclose other features, namely, simple construction, cheap cost of manufacture, and an easy and comprehensive operation.

With the above and other objects in view, my invention relates to such details of construction and in the arrangement and combination of parts, as will be hereinafter fully described and specifically pointed out in the appended claims.

In describing my invention in detail, reference will be had to the accompanying drawings, wherein like characters denote like or corresponding parts throughout the several views, and in which:

Figure 1 is a front elevation of my improved clasping device, illustrating the same in engagement with a button of the ordinary type. Fig. 2 is a side elevation of the device, such as shown in Fig. 1.

Referring now more particularly to the drawings, wherein is illustrated the preferred embodiment of my invention, the latter is illustrated as having engagement with a button of the usual type, the same being secured to an over-all bib. It will be appreciated that this clasp is designed for use in connection with buttons of numerous different configurations, thus it is not limited to its specific application shown.

My invention consists more essentially in the provision of a strand of relatively thick, resilient wire, bent intermediate its end, as shown at 10, thus forming a pair of sec-

tions of relatively the same length. The sections are now bent across each other, as illustrated in Figs. 1 and 2, to form a pair of relatively parallel arcuately curved strands 60 11 which extend upwardly toward each other near their upper extremities to form shoulders 12, as illustrated. Adjacent the upper extremities of the strands 11 the sections are bent to form diverging arms 13 of suitable 65 length, the latter being bent to form relatively parallel fingers 14, in order to provide a more suitable configuration for reception of the button when desired. Further, the fingers 14 are bent intermediate their ends to 70 form coils 15, which coils are in horizontal alinement with each other and designed for the purpose, presently set forth at length. The upper ends of the fingers 14 are turned, as shown at 16, to provide a suitable 75 supporting structure for reception of the lower extremity of the suspender element 17. A transverse element 18 connects the coils 15 of the fingers 14, the respective extremities thereof being bent, as shown at 19, for 80 joining the same in rigid relation with its component structure. The transverse element 18 is coiled intermediate its ends, as at 20, to provide a suitable supporting contrivance for handling the looped end 21 of 85 a clasping element 22. While one end of the clasping element is provided, as above mentioned, for engagement with the correspondingly joined portion of the transverse element 18, its other or lower extremity, is curved, as 90 shown at 23, for engagement with the curved portion 10 of the body. Here particular attention is called to the specific construction and configuration of the clasping element 22. This element extends along a line substantially with the vertical axis of the body and is curved interjacent its extremities, and more specifically extend adjacent the shoulders 12. The clasping device being curved downwardly adjacent the shoulders provides 100 capable resilient, standing means which normally engages the button when in place and serves to prevent longitudinal movement thereof, such as may be caused by pressure on the trousers or overalls.

In the operation of my invention, the portion of the apparel containing the button 24 is disposed adjacent the device, so as to allow the button to be introduced therein between the diverging arms 13. By drawing the device upwardly, the shank of the button will be forced between the shoulders 12 and al-

lowed to rest between the curved, engaging portions 11. The button in this position is under tension of the elastic, clasping element 22; the latter being designed to prevent accidental movement thereof.

The greatest of stress is laid upon the simplicity of my invention, in view of the fact that the same may be manufactured and placed upon the market at a minimum cost.

10 The advantages resultant from the use of my invention will be readily comprehended by those conversant with the crude and unsatisfactory devices heretofore provided in this art.

15 Such changes as are permissible by the subjoined claims may be resorted to without departing from the spirit of my invention.

Having thus fully described my invention, 20 what I claim as new and desire to secure by Letters Patent, is:

1. In a device of the character described, a body portion consisting of a strand of resilient material bent intermediate its length 25 to form side arms, said side arms being bent intermediate their length to form a bottom-receiving pocket and having their upper end portions bent to form attaching means, and a clamping element consisting of a 30 strand of resilient material extending across said bottom-receiving pocket and having its lower end connected with the lower-end portion of said body portion and having its upper-end portion connected with said side 35 arms.

2. In a device of the character described, a body portion consisting of a strand of material bent intermediate its end to form an eye having arms extending therefrom and 40 having their upper end portions formed into attaching means, opposite shoulders formed intermediate the ends of said arms to form a bottom-receiving pocket adjacent said eye, a transverse element connecting said arms, 45 and a clasping element extending longitudinally across said pocket and having one end connected with said transverse member and having its other end connected with said eye.

3. In a device of the character described, 50 a body portion including a strand of wire bent intermediate its ends to form sections of relatively the same length, inwardly projecting shoulders formed on said sections in-

termediate their ends to form a button receiving pocket, the free extremities of said sections being inturned to form supporting pintles, a transverse member connecting said sections intermediate their ends, and a resilient clasping element carried by said transverse member and said sections, and extending longitudinally thereof across said pocket and being bowed toward said pocket.

4. In a device of the character described, a body portion consisting of a strand of wire bent intermediate its ends to form sections of 65 relatively the same size, oppositely disposed shoulders formed from said sections, intermediate their ends to form a button receiving pocket, said sections being coiled intermediate their ends, the extremities of said 70 sections being inturned to form supporting pintles, a transverse member carrying said coils, said member being coiled intermediate its ends, a resilient clasping element engaging said last mentioned coil and extending 75 across said pocket, the other end of said clasping element engaging said body portion, as and for the purpose set forth and described.

5. In a device of the character described, 80 a body portion including a strand of material bent intermediate its ends to form sections of relatively the same length, said sections being bent adjacent their connection to form arcuate clasping members, the ends of 85 said members being bent inwardly to form oppositely disposed shoulders, said shoulders terminating in two diverging arm portions, parallel finger portions formed from said arm portions, said finger portions being 90 coiled intermediate their arms, the free extremity of said finger portions being bent inwardly to form a supporting pintle, a transverse member connecting said coils, said member being coiled intermediate its 95 ends, a clasping element having one end in engagement with said last mentioned coil, the other end of said clasping element engaging said body portion, said clasping element being bent downwardly adjacent said 100 shoulders, as and for the purpose set forth and described.
